UNITED STATES PATENT OFFICE.

CARL WINTER, OF CHICAGO, ILLINOIS.

HYDRAULIC DEVICE FOR ELEVATING LADDERS.

SPECIFICATION forming part of Letters Patent No. 423,851, dated March 18, 1890.

Application filed August 19, 1889. Serial No. 321,217. (No model.)

To all whom it may concern:

Be it known that I, CARL WINTER, a subject of the Emperor of Germany, residing at Chicago, in the county of Cook and State of Illinois, have invented a new, useful, and Improved Hydraulic Device for Elevating Ladders and Stand-Pipes, of which the following is a full, clear, and exact description, reference being had to the accompanying drawings, forming a part of this specification, in which—

Figure 1 is a plan view of a truck and fire-escape ladder, showing my improved hydraulic device for elevating said ladder. Fig. 2 is a side view of the same, partly in section, taken upon the line X, Fig. 1. Fig. 3 is a central longitudinal vertical sectional view in detail of the hydraulic apparatus; and Fig. 4 is a plan view of a modification of said device, showing the same applied to a stand-pipe.

Like letters of reference in the different figures indicate like parts.

The object of my invention is to provide a simple and effective motor or device for elevating firemen's ladders and stand-pipes, and for analogous purposes wherein a portable motor is required, which may be simple, powerful, and easily manipulated.

To these ends my invention consists in the combination of elements hereinafter more particularly described, and definitely pointed out in the claim.

Referring to the drawings, A represents a truck, upon which is pivotally mounted, preferably at the forward end, a frame B, resting by means of a fifth-wheel b, Figs. 2 and 3, upon a plate b², adjusted in the usual way, forming the center of oscillation. Extending upwardly from the frame B and rigidly secured thereto are brackets C C, in which is journaled a cross-bar c, to which is attached a ladder D or other structure intended to be moved in the arc of a circle, the attachment being near the lower end of the ladder.

Mounted upon the frame B and rigidly attached thereto is a hydraulic cylinder E, provided with the usual piston e and piston-rod e', passing through a bore e², which forms a guide therefor and enables the piston to work accurately in the cylinder. The cylinder E is provided with induction and eduction ports, at which are located valves F F', for

regulating the flow of liquid to the cylinder. A pipe f² serves to connect the induction-port with a pump G, Figs. 1 and 4, said pump being in turn connected by means of a pipe h either with a portable reservoir H, mounted upon the truck and normally filled with water, oil, or other liquid, or by a hydrant H', as indicated in the dotted lines in Fig. 1. A waste-pipe f³ is also connected with the induction-port. Bent arms J (better shown in Fig. 2) are attached to the lower end of the ladder, to the lower extremities of which are loosely attached pitman-rods k k, the opposite ends of which are secured to a cross-bar e³, attached to the piston-rod.

Upon the axle c is attached a ratchet c', adapted to be engaged by a pawl c², for the purpose of preventing the fall of the ladder in the event of the breakage or failure to act of other parts.

In Fig. 4 I have shown my improved elevating device applied in a similar manner to a stand-pipe D'. In such a case I prefer to make the axle c hollow, as indicated in dotted lines, so that the water-supply pipe L may communicate directly therewith, and the water may be permitted to flow through it at any elevation of the stand-pipe.

The operation of my improved elevating device is as follows: Assuming the ladder or stand-pipe to be in a normal position, the valve f is opened and the valve f' closed, as shown in Fig. 1. Upon operating the pump the liquid is forced into the cylinder E, the piston e pushed back, when the links k k drawing upon the lever-arms F tilts the ladder or other structure upon its axis and elevates it to the desired position. The frame B may then be turned upon its vertical axis for the purpose of adjusting the ladder with reference to the building against which it is to be placed.

The lowering of the ladder may be accomplished by opening the valve f' and permitting the water to flow out more or less, according to the extent to which it is desired to have the ladder descend.

Having thus described my invention, what I claim, and desire to secure by Letters Patent, is—

The combination, with a vehicle, of the circular rotary frame B, centrally pivoted, braces

C C, ladder D, trunnioned thereto, hydraulic cylinder, bracket J, a pitman connecting the same to said hydraulic cylinder, reservoir H, mounted upon the vehicle, pump G, in operative connection therewith and with said cylinder, an eduction-pipe, and valves f f', all combined and arranged substantially as shown and described.

In testimony whereof I have signed this specification, in the presence of two subscribing witnesses, this 10th day of August, 1888.

CARL WINTER.
